UNITED STATES PATENT OFFICE.

HERMAN BUHLMAN, OF PROVIDENCE, RHODE ISLAND.

WATCHCASE BEZEL.

Application filed October 9, 1924. Serial No. 742,552.

To all whom it may concern:

Be it known that I, HERMAN BUHLMAN, a citizen of Switzerland, residing at Providence, in the county of Providence and 5 State of Rhode Island, have invented certain new and useful Improvements in Watchcase Bezels, of which the following is a specification.

This invention relates to an improved 10 construction of watch case bezel; and has for its object to provide a bezel member having a front rim with an opening formed therein, the opening being provided with an inwardly flaring edge forming a seat for a 15 crystal which may be positioned from the inside of the bezel and a fastening member being provided for locking the crystal in its seat.

A further object of the invention is the 20 provision of means on the locking member for holding the watch movement on its support in the casing.

With these and other objects in view, the invention consists of certain novel features 25 of construction, as will be more fully described and particularly pointed out in the appended claims.

In the accompanying drawings:

Figure 1 is a face view of the watch having 30 my improved bezel.

Figure 2 is a perspective view of the locking frame member.

Figure 3 is a perspective view showing a portion of the inner side of the bezel body 35 member.

Figure 4 is an edge view of the locking frame member.

Figure 5 is a section on line 5—5 of Figure 1 looking in the direction of the arrow.

Figure 6 is an enlarged view of the mechanism shown in Figure 5.

Figure 7 shows the bezel frame member in position to be carried upward to its seat before the movement is inserted into the 45 casing.

It is found in the practical construction of watch cases, particularly cases for the small for the small wrist type of watch, that where the crystal is snapped in from the 50 outside of the case that this operation is very slow even where skilled labor is employed and also owing to the large percentage of breakage of these crystals this means of positioning them is quite unsatisfactory. It is also found that when a 55 crystal is snapped in from the front it is

not tight and therefore, dust and foreign matter works in and clogs the movement; and to obviate these difficulties I have formed a bezel member having an inturned 60 front bezel rim with an opening for the crystal, the edge wall of the opening flaring inwardly to provide a beveled seat, and I have also provided a frame member for pressing and locking the crystal in this 65 beveled seat so tightly as to exclude moisture and foreign matter therefrom; also I have provided in this frame member means for pressing the movement or works of the watch to its support in the casing without 70 the necessity of employing other fastening for this purpose; and the following is a detailed description of the present embodiment of my invention and showing one means by which these advantageous results may be 75 accomplished:—

With reference to the drawings 10 designates a watch case which is formed of a lower body portion 11 and having an inwardly extending flange 12 and an upper body 80 portion 13 into which this flange 12 closely fits to secure the two members of the body together. A movement 14 has an extending dial portion 15 supported on this flange 12 in the lower casing, the upper body portion 85 being preferably formed of sheet stock having a front, inturned bezel rim 16 having an opening for the crystal 17. The edge of the inturned, laterally extending rim is turned downwardly as at 18 forming an inwardly- 90 flaring or inwardly beveled seat, the marginal edge of which overhangs the face of the watch and against which the edge of the crystal 17 is fitted to seat from the inner side outwardly.

Owing to the fact that this bezel and body member are formed of sheet stock and shaped more especially by a bending operation the seat 19 for the crystal, may be made very accurately and as the edge portion of the crystal, itself, is formed by machinery, it may be caused to fit so closely to its seat as to render it practically air tight.

In addition to turning inwardly the edge of the stock about the opening in the rim, I have provided a broad seating surface 19 for the crystal 17 which inturned edge also provides a flange to which the bezel locking frame may be readily secured. In order to hold this crystal to its seat, I have 105 provided a bezel locking frame 20 which is herein shown as being provided with two 110

25 pairs of upstanding resilient fingers 21 which are adapted to snap over the outside of this inwardly extending flange 18 and so lock the frame in position as to press and effectively secure the crystal to its seat. And further, I have provided two sets of downwardly turned flange members 22 on this bezel locking frame which serve to rest upon the face or dial 23 of the movement 14, when 10 the lower body portion is forced into the upper body portion to carry the movement up to its operating position, as illustrated in Figure 5.

15 My improved watch casing is very simple in construction and by its use a crystal may be inserted from the back into the bezel member with great rapidity, without the necessity of employing highly skilled labor as is necessary to set a crystal from the front and 20 also breakage is reduced to a minimum; then again by simply snapping the locking frame into position and connecting the lower body portion with its movement to the front body portion, both the bezel and the watch movement are automatically bound in position by 25 spring pressure by the fingers and the flanges on the bezel locking frame.

30 The foregoing description is directed solely towards the construction illustrated, but I desire it to be understood that I reserve the privilege of resorting to all the mechanical changes to which the device is susceptible, the invention being defined and limited only by the terms of the appended claims.

35 I claim:

1. In a watch case, a body member formed of sheet stock having a bezel rim with an 40 inturned inwardly flaring marginal flange forming a beveled seat for the crystal, and means beneath the crystal for pressing it to its seat.

45 2. In a watch case, a bezel member having a front rim with an opening formed therein, an inwardly flaring edge providing a seat for the crystal, and a bezel frame having members to snap into engagement with the stock about the opening to hold the crystal to its seat.

50 3. In a watch case a body member formed of sheet stock having an inturned front bezel

rim with an opening for the crystal the edge wall of the opening flaring inwardly providing a beveled seat for the crystal, and a frame member fitted inside the bezel rim to hold the crystal to its seat.

4. In a watch case, a bezel member having an opening in its frame for a crystal, the edge about the opening being turned inwardly forming a seat for the crystal and a bezel frame having means to snap over said in-turned edge to lock the crystal to its seat. 55

5. In a watch case, a bezel member having an opening in its front with an inturned inwardly flaring marginal flange forming a beveled seat for the crystal, and a bezel frame having means to snap over the in-turned flange to retain the crystal in its seat. 65

6. In a watch case, a bezel member having an opening in its front with an inturned inwardly flaring marginal flange forming a beveled seat for the crystal, and a bezel frame having upstanding resilient fingers to snap over said inturned flange to hold the crystal to its seat. 70

7. In a watch case, a bezel member having an opening with an inturned inwardly flaring edge forming a seat for the crystal, means for supporting a watch movement in the casing, a bezel frame intermediate the crystal and the movement, and having means 80 for holding both in operating position. 75

8. In a watch case, a bezel member having an opening with an inturned inwardly flaring edge forming a seat for a crystal, means for supporting a watch movement in the casing, a bezel frame member having means for holding the crystal to its seat and also for binding the movement to its support. 85

9. In a watch case, a bezel member having an opening in its front with an inturned inwardly flaring marginal flange forming a beveled seat for the crystal, means for supporting a movement in the casing, and a frame member having resilient means to snap into engagement with said flange to hold the lens to its seat and also a member for simultaneously pressing said movement to its support. 90

95 In testimony whereof I affix my signature.
HERMAN BUHLMAN.
